UNITED STATES PATENT OFFICE.

WILLIS E. LINDLEY, OF WALLA WALLA, WASHINGTON.

CHILD'S FOLDING SULKY.

1,003,622.

Specification of Letters Patent. Patented Sept. 19, 1911.

Application filed May 11, 1911. Serial No. 626,477.

To all whom it may concern:

Be it known that I, WILLIS E. LINDLEY, a citizen of the United States, residing at Walla Walla, in the county of Walla Walla and State of Washington, have invented certain new and useful Improvements in Children's Folding Sulkies, of which the following is a specification, reference being had to the accompanying drawings.

This invention is an improved foldable vehicle, especially a folding sulky for use by and for children, the object of the invention being to provide an improved vehicle of this kind which is strong and durable, 15 may be readily manufactured at a minimum cost, and which is capable of being very compactly folded and disposed for transportation or storage.

The invention consists in the construction, 20 combination and arrangement of devices hereinafter described and claimed.

In the accompanying drawings Figure 1 is a side elevation of a folding sulky constructed in accordance with my invention; 25 Fig. 2 is a rear elevation of the same; Fig. 3 is a plan of the same; Fig. 4 is a similar view, showing the parts folded; and Fig. 5 is an inverted plan, showing the parts folded.

The body or seat 1 of my improved sulky 30 is here shown as rectangular in form. On the bottom thereof, near the sides and at a suitable distance from the front side of the seat or body, are blocks 2, 3, each of which is provided with a pair of downwardly extending spaced lugs, the lugs of the block 2 being indicated at 4 and those of the block 3 being indicated at 5 and being longer, in vertical extent, than the lugs 4. Hangers 6 and 7, which are unequal in length, are 35 respectively pivotally mounted at the upper ends between the lugs of the blocks 2, 3, the pivot bolts of the said hangers being indicated at 8, 9. Hence, the hanger 6 is adapted to be extended downwardly from the seat or body and disposed in a vertical position and is, also adapted to be folded transversely across and to lie against the bottom of the body. The hanger 7 is also adapted for movement angularly in a vertical plane and when 45 folded lies out of the plane of the hanger 6.

Each hanger is provided near its lower end with an outwardly extending spindle 10 and the vehicle wheels 11 are mounted on the said spindles. Owing to the difference in 55 length between the lugs 4 and the lugs 5,

after the hanger 6 has been folded against the bottom of the body, the hanger 7 may then be folded and disposed parallel therewith and with its wheel bearing on the wheel of the hanger 6. The hangers are provided 60 on their inner sides with rearwardly directed clips 12.

The pole or tongue 13 comprises the rear section 14 and the front section 15. The meeting ends of the said sections are beveled 65 and the said sections are hinged together at the joint by a hinge 16 which is secured on the lower side of the tongue and hence the section 15 is adapted to be extended from and in line with the section 14 and is also 70 adapted to be folded upon the same. A sleeve clamp 17 is fitted on the tongue and is movable so that it may cover the joint between the two sections, so as to secure them together and may be moved inwardly on the front section 15 to clear the section 14 and allow the latter to be folded on the section 14. The rear section of the pole or tongue 75 is provided on its upper side, at a suitable distance from its rear end, with a rearwardly directed clip 18.

A foot rest 19 is carried by the tongue. This foot-rest comprises a supporting bar 20, which has its rear end pivotally connected to the rear section of the tongue as 85 at 21, is provided at a suitable distance from its front end with a cross bar 22 which forms a rest for the child's feet, the front end of the said bar 20 being pivotally connected as at 23 to the lower end of a supporting bar 24, the upper end of the said supporting bar being pivotally connected as 90 at 25 to the under side of the clamp sleeve 17. I also provide a locking bail 26. This is substantially U-shaped and has the upper 95 ends of its arms pivotally connected as at 27 to the under side of the body or seat. The cross bar 28 of this locking bail is provided at its center with a cranked portion 29 for engagement with the clip 18 of the tongue, the side or end bars of the locking bail being adapted for engagement with the clips 12 of the hangers so as to lock the hangers in place when vertically disposed and the sulky is in use.

A pivot bolt 29 is connected to the seat or body near the front side thereof and at a point midway between its sides and has a downwardly extending yoke 30, between the arms of which the rear section 14 of the 100 105 110

tongue is pivoted as at 31. Hence, the tongue is connected to the seat or body for transverse angular movement so that it may be disposed in engaged position with the locking bail as shown in Figs. 1, 2 and 3 5 or it may be swung transversely and disposed across the front of the body when the sulky is folded, as shown in Fig. 5.

On the upper side of the seat is a rail 10 which comprises a pair of side sections 32 and a rear section 33. Each section is made from a single rod of suitable gage and is substantially U-shaped. The ends of the side sections 32 are pivotally connected to the seat as at 34 and those of the rear section 33 are pivotally connected to the seat as at 35. Hence, the sections of the rail are adapted to be folded upon the upper side of the seat and they are also adapted to be extended upwardly therefrom. The side sections 32 are provided at their rear upper corners with offset loops 36, which may be engaged with the rear section 33, when the latter is set up, and hence caused to lock the rear section in place and it will be understood, that the upper corners of the rear section also lock the side sections in place so that the said folding sections of the rail of the seat are interlocking.

30 While I have herein shown and described what I now consider the preferred embodiment of my invention I will have it understood that minor changes may be made in the form, proportions and construction of 35 the several parts without departing from the spirit of my invention and within the scope of the appended claims.

Having thus described my invention I claim:

40 1. In a vehicle of the class described, the combination of a body, hangers pivotally connected to the body and foldable under

and across the same, said hangers having spindles for the wheels, a tongue pivotally connected to the body and having a rearwardly extending portion, and a locking bail pivotally connected to the body and adapted to engage the hangers and tongue to lock them in set up position.

2. In a vehicle of the class described, the combination of a body, a tongue connected thereto for angular movement and having a rearwardly extending portion provided with an attaching device, hangers pivotally connected to the body and foldable across the under side thereof, the said hangers being provided with outwardly extending spindles for the wheels and also provided, on their inner sides, with attaching devices, and a locking bail connected to the body and adapted to be engaged by the attaching devices of the tongue and hangers to lock the tongue and hangers in set up position.

3. A vehicle of the class described having a tongue comprising a rear section and a front section pivotally connected together so that the front section may be folded against the rear section, a clamping sleeve movable on the tongue across the joint between the sections thereof and a foot rest comprising a lower bar pivotally connected at its rear end to the rear section of the tongue, and a supporting bar having its lower end pivotally connected to the front end of the lower bar, and its upper end pivotally connected to the clamping sleeve.

In testimony whereof I hereunto affix my signature in the presence of two witnesses.

WILLIS E. LINDLEY.
